(57) **CLAIM**

The ornamental design for a probe, as shown and described.

DESCRIPTION

FIG. 1 is a front elevational view of a first embodiment of a dental handpiece showing the present invention;

FIG. 2 is a left side view thereof;

FIG. 3 is a rear elevational view thereof;

FIG. 4 is a right side view thereof;

FIG. 5 is a top plan view thereof;

FIG. 6 is a bottom plan view thereof; and

FIG. 7 is a perspective view;

FIG. 8 is a front elevational view of a second embodiment;

FIG. 9 is a left side view thereof;

FIG. 10 is a rear elevational view thereof;

FIG. 11 is a right side view thereof;

FIG. 12 is a top plan view thereof;

FIG. 13 is a bottom plan view thereof; and

FIG. 14 is a perspective view;

FIG. 15 is a front elevational view of a third embodiment;

FIG. 16 is a left side view thereof;

FIG. 17 is a rear elevational view thereof;

FIG. 18 is a right side view thereof;

FIG. 19 is a top plan view thereof;

FIG. 20 is a bottom plan view thereof; and,

FIG. 21 is a perspective view.
